UNITED STATES PATENT OFFICE

2,493,384

TREATMENT OF HYDROCARBONS

Daniel E. Bergen, Phillips, Tex., assignor to Phillips Petroleum Company, a corporation of Delaware

Application May 27, 1946, Serial No. 672,475

1 Claim. (Cl. 196—148)

1

This invention relates to the conversion of hydrocarbons. In one aspect this invention relates to the purification of acid-soluble oils. In another aspect this invention relates to the alkylation of hydrocarbons in the presence of a hydrofluoric acid alkylation catalyst. In another and more particular aspect this invention relates to the production of a drying oil.

In the conversion of hydrocarbons in the presence of inorganic acid catalysts, such as hydrofluoric acid or sulfuric acid, acid-soluble oils are formed as by-products of the conversion reaction and contaminate the acid phase of the conversion process. For example, in the alkylation of an alkylatable hydrocarbon with an olefin in the presence of a hydrofluoric acid alkylation catalyst, acid-soluble oils accumulate in the acid phase to such an extent as to decrease the activity of the catalyst and yield of product. The contamination of the acid phase of such an alkylation process with acid-soluble oils necessitates the removal of acid-soluble oils from the acid. As the acid is also contaminated with water which is detrimental to the acid activity the acid-soluble oils are usually removed during the purification of the acid to remove the water therefrom. The separated oil phase contains from about 0.5 to about 15 weight per cent hydrogen fluoride and in many cases a small amount of water. Since this acid-soluble oil as separated has had little value, it has been disposed of as a waste product. However, its disposal constitutes a dangerous health hazard since the acid in the oil cannot be neutralized because of the presence of the oil. From the viewpoint of the disposal of the acid-soluble oils and for their possible usefulness, it is much to be desired to provide a method to remove the acid from the acid-soluble oils.

The object of this process is to provide a method for the separation and recovery of acid-soluble oils from the effluent of a hydrocarbon conversion process.

It is another object to decrease the difficulty of disposal of acid-soluble oils.

It is another object to purify acid-soluble oils obtained from a hydrocarbon conversion process using an inorganic acid catalyst.

A further object of this invention is to provide a process for the production of acid-soluble oils of high quality and high purity.

Still another object is to manufacture a drying oil of superior characteristics to other known drying oils.

A further object is to decrease the difficulty of disposal of oil wastes from a hydrocarbon conversion process using an inorganic acid catalyst.

Other objects and advantages will become apparent to those skilled in the art from the accompanying description and disclosure.

This invention comprises a method for the re-

2

moval of acid-soluble oils from a hydrocarbon conversion effluent and the purification of these acid-soluble oils so that they may be recovered as a useful and valuable product or disposed of without difficulty. Accordingly in a process for the conversion of hydrocarbons in the presence of a hydrofluoric acid catalyst in which the hydrocarbon conversion effluent is separated into a liquid hydrocarbon-rich phase and a heavier liquid hydrofluoric acid-rich phase and the hydrofluoric acid-rich phase is treated to remove water and acid-soluble oils therefrom, such as by a series of distillations, the acid-soluble oils which are recovered during the treatment of the hydrofluoric acid catalyst and which are contaminated with water within the range between about 5 and about 15 weight per cent and with hydrofluoric acid within the range between about 0.5 and about 10 weight per cent are subsequently treated to remove hydrogen fluoride therefrom. This treatment to remove hydrogen fluoride from the acid-soluble oils comprises admixing approximately equal volumes of water and acid-soluble oil and allowing the resulting mixture of water and acid-soluble oil to settle at a temperature between about 175 and about 210° F. for sufficient length of time for a phase separation to occur and to allow the water phase to extract hydrogen fluoride from the hydrocarbon phase. It is extremely important that sufficient time be allowed for the water phase to extract hydrogen fluoride from the hydrocarbon phase at the appropriate temperature, such time being at least about one hour and preferably between about 3 and about 5 hours. The ratio of water to acid-soluble oils in the above treatment is also important and should be at least about a 1:1 volume ratio and may be as high as about a 3:1 volume ratio. In most instances the oil itself is not heated but water at a temperature between 200 and 210° F. is admixed therewith which raises the temperature of the resulting mixture sufficiently high to achieve adequate extraction of the hydrogen fluoride from the acid-soluble oils. The process may be carried out in either a batch operated process or a continuous operated process without departing from the scope of this invention and with equal successful extraction of acid from the acid-soluble oil fraction.

In a batchwise process, the washing treatment of the acid-soluble oils may be repeated as many times as desired and as is necessary to remove a sufficient amount of the hydrogen fluoride from the acid-soluble oil fraction. Figures 1 and 2 of the drawings show graphically the composition of the hydrocarbon phase after treatment according to this invention and after settling for a period of time indicated on the abscissa of the graphs. The ordinate of the graph of Figure 1 indicates the composition of the hydrocarbon

phase with respect to hydrogen fluoride content. The ordinate of the graph of Figure 2 indicates the composition of the hydrocarbon phase with respect to the water content. It is clear from Figures 1 and 2 that to obtain maximum efficiency of the washing step at least one hour residence time should be allowed for either a batchwise or continuous process. The curves of Figures 1 and 2 were derived from data shown in Table II of Example II of this specification.

Typical acid-soluble oil fractions which may be treated according to the process described herein vary considerably in composition, but are, in general, normally liquid and are soluble in hydrogen fluoride and partially soluble in water and in hydrocarbons. The acid-soluble oil fractions vary in A. P. I. gravity between about 15 and about 30 degrees and possess an iodine number (a measurement of unsaturation) between about 175 and about 250. Generally, the 10-90 volume per cent boiling range determined by vacuum distillation and corrected to a pressure of 760 mm., is within the range between about 300 and about 1000° F. About 60 to 85 weight per cent of the acid-soluble oil fractions comprise non-volatile material at atmospheric pressure. Acid and water remaining in the acid-soluble oil fractions after treatment of the fractions are less than about 0.05 weight per cent and about 2 weight per cent, respectively.

The invention may perhaps be more adequately understood by reference to Figure 3 of the accompanying drawings and the description thereof. Figure 3 represents diagrammatically the preferred arrangement of apparatus elements and flow of materials thereto in which the process of the present invention may be practiced. While the elements essential to the understanding of the invention are shown in Figure 3, it will be appreciated that various auxiliary pieces of equipment may be provided by one skilled in the art without departing from the scope of this invention. Since the alkylation of an alkylatable hydrocarbon in the presence of a hydrofluoric acid catalyst produces a considerable amount of acid-soluble oils in the liquid acid phase, usually between about 5 and about 20 per cent, this invention as applied to such an alkylation process will be described.

In the alkylation of isobutane with olefins in the presence of hydrofluoric acid as the alkylation catalyst, a suitable and typical feed stock of the hydrofluoric acid alkylation in which the acid-soluble oils are a by-product appears in Table I below:

Table I

Component	Mol per cent
Isobutane.....	68
Isobutylene.....	4
Normal butylene.....	7
Butane.....	20
Other hydrocarbons.....	1
	100

Such a hydrocarbon feed enters reaction zone 6 through line 4 and is intimately contacted therein with hydrofluoric acid, which enters through line 7 and which has a titratable acidity between about 80 and about 95 per cent by weight. The overall mol ratio of paraffin to olefin is usually from about 4:1 to about 20:1 in the combined feed and recycle (line 14) and much higher in the reaction zone itself. The time of residence of the reaction mixture in the reaction zone 6 is

usually from about 5 to about 15 minutes but it may be for shorter or longer periods as desired. The volume ratio of acid to hydrocarbon is between about 0.5:1 and about 2:1, generally about 1:1, although other ratios may be maintained. The hydrocarbon feed stock enters the alkylation process at a temperature of about 80 to about 100° F. under pressure of about 90 to about 100 pounds per square inch gage. Should it be desired, however, both higher pressures and higher temperatures may be used. In general, only sufficient pressure to ensure liquid phase operation is necessary. From reaction zone 6 a hydrocarbon conversion effluent is passed by line 8 to separation zone 9 in which the effluent separates into two liquid phases—namely, a lighter hydrocarbon-rich phase and a heavier hydrogen fluoride-rich phase. The hydrogen fluoride-rich phase is withdrawn from the bottom of separator 9 through line 19 to be recycled as a catalyst for the alkylation reaction through lines 19 and 7. Fresh make-up hydrofluoric acid may be added to the system through line 7 when desired. When it is desirable to remove water and to recover acid-soluble oils from the acid-phase in order to ensure the proper function of the catalyst or to recover the acid-soluble oils as a valuable by-product, a portion or all of the hydrogen fluoride phase is passed through line 21 to a purification unit 22, the operation of which will be discussed hereinafter. An azeotropic mixture of water and hydrogen fluoride and acid-soluble oils are separately removed from purification unit 22 through lines 24 and 26, respectively. A purified anhydrous acid phase is passed from purification unit 22 through lines 23, 19 and 7 to reactor 6.

A liquid hydrocarbon-rich phase containing dissolved hydrogen fluoride passes from separator 9 through line 11 to separating unit 12. In separating unit 12, which may comprise a single or a series of distillation zones, approximately an azeotropic mixture of hydrogen fluoride and low-boiling hydrocarbons, such as isobutane, is separated and is passed therefrom through line 13 back to separator 9. Isobutane is separated from the reaction effluent in separating unit 12 and recycled to reactor 6 through line 14. Normal butane and other intermediary products are withdrawn from separating unit 12 through line 16. The normal butane may be isomerized to isobutane and used as a portion of the feed. The alkylation product comprising a light alkylate and heavy alkylate is withdrawn from separating unit 12 via line 17 and may be passed to further equipment (not shown) for purification and separation.

Referring to purification unit 22, several methods are known to those skilled in the art for removing water and acid-soluble oils from the acid phase. A typical and generally used method comprises passing the acid phase to a series of distillation columns. The first column comprises, in general, a flash distillation column in which hydrogen fluoride and water pass overhead as a vapor and the acid-soluble oils containing some free hydrogen fluoride is removed as a bottom product. The hydrogen fluoride and water overhead after condensation is passed to a second distillation column, from which substantially anhydrous hydrogen fluoride is removed as an overhead fraction and a liquid azeotropic mixture of water and hydrogen fluoride is removed as a bottom fraction. In some instances a single distillation column may be used to purify the acid phase. An acid-water azeotrope containing the acid-

soluble oils is removed from the bottom of the single distillation column. The liquid bottom fraction is allowed to settle for sufficient length of time to form a hydrocarbon phase and a water-acid phase. The hydrocarbon phase comprises the acid-soluble oils. In either of these methods for recovering acid-soluble oils from the acid phase, the acid-soluble oil fraction recovered contains between about 5 and about 15 weight per cent water and between about 0.5 and about 10 weight per cent hydrogen fluoride. The acid-soluble oils constitute about 10 weight per cent of the original acid phase. Often economic and operational considerations dictate the omission of the aforementioned step for the separation of the acid-soluble oil from the resulting acid-water azeotrope in purification unit 22. When this optional separation step is omitted, a mixture of water, acid and acid-soluble oil is passed directly through line 26 to the washing step hereinafter described and line 24 is not used.

In order to purify such an acid-soluble oil fraction according to this invention, the acid-soluble oil fraction is passed from acid purification unit 22 through line 26 to mixing or prewash tank 27. The acid-soluble oils from line 26 are extruded through a perforated ring (not shown) into a hot layer of water (between about 200 and about 210° F.) in tank 27. The acid-soluble oils and water in tank 27 may be agitated by mechanical means if desired. Approximately 90 per cent of the hydrogen fluoride in the acid-soluble oil fraction is removed in tank 27 and is removed therefrom as an aqueous solution through line 29. Hot water at a temperature between about 200 and about 210° F. is passed into tank 27 through line 33. The washed acid-soluble oil fraction rises to the top of the water layer in tank 27 and overflows therefrom through line 28 and is passed to a settling tank 31. Hot water at a temperature between about 200 and about 210° F. is introduced into line 28 through line 32 and is admixed therein with the washed acid-soluble oil fraction from tank 27 in about 2:1 volume ratio. A mixing pump or orifice device (not shown) may be inserted on line 28 to thoroughly mix the water and the acid-soluble oil fraction prior to introduction into settling tank 31. In settling tank 31 a liquid hydrocarbon phase comprising purified acid-soluble oils and a liquid water phase is separated by settling for several hours. The water phase contains hydrofluoric acid extracted from acid-soluble oil fraction and is removed therefrom through line 37. This water-acid phase may be withdrawn from the system through line 37 or may be passed through lines 38, 32 and 33 to prewash tank 27, if desired. The purified acid-soluble oil fraction forms an upper layer in tank 31 and is withdrawn therefrom through line 36. Impurities in the acid-soluble oil fraction withdrawn through line 36 range between about 0.03 and about 0.01 per cent by weight of acid and between about 0.6 to about 0.4 per cent by weight of water.

A temperature between about 175 and 210° F., preferably above 200° F., and a residence time between about 1 to about 5 hours of the liquid mixture is maintained in tank 31.

The acid-soluble fraction purified according to this invention is of very high purity and is useful as a drying oil. Comparative tests indicate that the purified acid-soluble oils have a higher viscosity, a higher per cent nonvolatility, a higher iodine number and a lower polymer color than other similar drying oils. Also the purified acid-

soluble oil fraction appears to form a tougher, harder film when exposed to the air than other drying oils. When it is not desired to recover the acid soluble oil fraction as a product, the disposal problem is minimized by such a treatment since no hydrogen fluoride is contained in the oils but remains in the water phase, which may be neutralized with an alkali in the conventional manner.

10 The following examples are offered as illustrative of the operation and product of the present invention and should not be construed to unnecessarily limit this invention.

EXAMPLE I

15 An acid-soluble oil fraction from an alkylation process acid regeneration unit, such as unit 22 of Figure 3, containing approximately 7 weight per cent hydrogen fluoride was charged to a pre-wash tank, such as tank 27. After the acid-soluble oil fraction has passed through an approximately equal volume of water at about 200° F. in this prewash tank, it contained about 0.2 weight per cent hydrogen fluoride. The pre-washed oil was removed from the prewash tank and mixed with an equal volume of hot water at approximately 210° F. in a mixing pump and then passed to a cooling tank and allowed to stand at about 200° F. After about 45 minutes 20 the acid-soluble fraction contained about 0.008 weight per cent hydrogen fluoride, and after nearly two hours contained only about 0.001 weight per cent hydrogen fluoride. The wash water containing the acid was oil free and could 25 be easily neutralized without the interference encountered when oil was present.

EXAMPLE II

30 Five gallons of an acid-soluble oil fraction from an acid purification unit of an isobutane alkylation process was charged to a tank equipped with steam coils. The oil was heated to a temperature of approximately 210° F. During the same period, water in a secondary tank was heated to its boiling point. The hot oil and water were fed through a pump in about a 1:1 ratio and charged back to the secondary tank for settling. After the oil in the charge tank had all been 35 pumped, the mixture was allowed to settle 30 minutes. The water was drained and the oil transferred to the first tank, after which the procedure was repeated with fresh water.

35 Following the second wash the separating mixture was kept hot by an exterior coil to facilitate phase separation. Samples of the oil were taken after $\frac{1}{4}$, $\frac{1}{2}$, 1, 2, etc. hours and the hydrogen fluoride and water content determined. The 40 composition of the hydrocarbon phase with respect to water and hydrogen fluoride for the various residence times is indicated in Table II below. The data of Table II is shown graphically in Figure 1 and 2 of the drawing.

Table II

Residence Time	Per cent by weight, H_2O	Per cent by weight, HF
15 minutes	7.4	0.086
30 minutes	3.4	0.054
1 hour	1.37	0.034
2 hours	0.73	0.030
4 hours	0.45	0.024
5 hours, 15 minutes	0.27	0.022
6 hours	0.27	0.021
7 hours	0.23	0.010

EXAMPLE III

Characteristics of acid-soluble oil fractions purified according to the treatment of this invention are shown in Table III below:

Table III

Sample	Flash Point	Fire Point	Saybolt Universal Viscosity at 210° F.	A. P. I. Gravity	I ₂ No.	Per Cent Non-vol.	Polymer Color
I	200	210	52.6	22.9	218	75.6	3
II	210	255	82.1	20.4	215	80.4	3½
III	215	275	78.9	19.9	206	82.0	4½
IV	210	275	58.6	20.7	203	81.1	4

Various apparatus elements, such as valves, cooler, heater, mixers, etc. have been omitted from the drawing for the matter of convenience. Consequently various alterations and modifications may become apparent to those skilled in the art without departing from the scope of this invention.

I claim:

In a process for the alkylation of hydrocarbons in the presence of a hydrofluoric acid catalyst in which an effluent from said alkylation is separated into a hydrocarbon-rich phase and a liquid hydrofluoric acid-rich phase and the acid-rich phase is treated to separately recover therefrom said acid catalyst and an acid-soluble oil fraction containing residual acid, the method for treating said acid-soluble oil fraction to prepare an acid-soluble oil product and an innocuous aqueous suspension by-product, which comprises admixing therewith at least an equal vol-

ume of hot liquid water at a temperature of about 200° F. to 210° F., allowing the resulting liquid mixture of water and acid-soluble oil to settle for a period of at least one hour at a temperature between about 175° and about 210° F. under conditions such that a liquid hydrocarbon phase and a liquid water phase separate, thereby extracting said residual acid from the acid-soluble oil fraction, recovering said hydrocarbon phase substantially free from acid as a purified acid-soluble oil product of said extraction, separately recovering said liquid water phase substantially free of oil and containing said residual acid and neutralizing said liquid water phase with an alkali to form an innocuous suspension of a fluoride salt before disposal thereof as said by-product of the process.
